US00D507094S

(12) **United States Design Patent** (10) Patent No.: **US D507,094 S**
(45) Date of Patent: **** Jul. 12, 2005**

(54) **SPRING ELEMENT FOR AN ARTICLE OF FOOTWEAR**

(76) Inventor: **Robert E. Lyden**, 18261 SW. Fallatin Loop, Aloha, OR (US) 97007

(**) Term: **14 Years**

(21) Appl. No.: **29/167,845**

(22) Filed: **Sep. 20, 2002**

(51) LOC (8) Cl. **02-99**

(52) U.S. Cl. **D2/946**

(58) Field of Search D2/896, 902, 907, D2/946, 972, 977, 905, 955, 967; 36/7.8, 27, 38

CLAIM

The ornamental design for a spring element for an article of footwear, as shown and described.

DESCRIPTION

FIG. 1 is a lateral side view of a spring element for an article of footwear embodying my new design and shown for a left foot;

FIG. 2 is a medial side view thereof;

FIG. 3 is a bottom plan view thereof;

FIG. 4 is a rear elevational view thereof;

FIG. 5 is a front elevational view thereof;

FIG. 6 is a lateral side view of a modified form showing a non-tapered spring element for an article of footwear and shown for a left foot;

FIG. 7 is a medial side view of FIG. 6;

FIG. 8 is a bottom plan view of FIG. 6;

FIG. 9 is a rear view of FIG. 6;

FIG. 10 is a front view of FIG. 6;

FIG. 11 is a lateral side view of a modified spring element for an article of footwear having asymmetrical curvature on the medial and lateral sides, shown for a left foot;

FIG. 12 is a medial side view of FIG. 11;

FIG. 13 is a bottom plan view of FIG. 11;

FIG. 14 is a rear view of FIG. 11;

FIG. 15 is a front view of FIG. 11;

FIG. 16 is a side view of a tapered inferior spring element for an article of footwear; and,

FIG. 17 is a side view of a non-tapered spring element for an article of footwear; the dotted line representations of the Figures being for illustrative purposes only and form no part of the claimed design.
